DESIGN FOR A COMBINED CIGARETTE HOLDER AND DISPENSER

Maurice J. Schipper, San Diego, Calif.

Application January 10, 1948, Serial No. 143,647

Term of patent 3½ years

(Cl. D85—2)

To all whom it may concern:

Be it known that I, Maurice J. Schipper, a citizen of the United States of America, residing at San Diego, in the county of San Diego and State of California, have invented a certain new, original, and ornamental Design for a Combined Cigarette Holder and Dispenser, of which the following is a specification, reference being had to the accompanying drawing, forming a part thereof.

Fig. 1 is a top plan view of a combined cigarette holder and dispenser, showing my new design;

Fig. 2 is a side elevational view thereof; and

Fig. 3 is an end view thereof.

I claim:

The ornamental design for a combined cigarette holder and dispenser, substantially as shown.

MAURICE J. SCHIPPER.
